UNITED STATES PATENT OFFICE.

CHARLES C. WIENTGE, OF PROVIDENCE, RHODE ISLAND, ASSIGNOR TO THE
HOWARD STERLING COMPANY, OF SAME PLACE.

DESIGN FOR A PITCHER.

SPECIFICATION forming part of Design No. 23,890, dated December 25, 1894.

Application filed October 29, 1894. Serial No. 527,361. Term of patent 7 years.

To all whom it may concern:

Be it known that I, CHARLES C. WIENTGE, of Providence, in the county of Providence and State of Rhode Island, have invented and produced a new and original Design for Pitcher-Bodies, of which the following is a full, clear, and exact specification, reference being had to the accompanying drawings, forming part thereof.

Figure 1 represents an elevation of a pitcher, the main portions of the new design being shown in solid lines. Fig. 2 represents a cross-sectional view of the body portion.

The main features of the new design consist in the conical base having its edge divided into six vertical planes, the convex beading or rib above the base, the inverted conical body divided into six flattened surfaces gradually widening toward the top, and the short concave neck finished in a pitcher-shaped edge which is surrounded by a beaded border.

In the drawings 5—5 represent the vertical planes forming the edge of the base 6 the surface of which, above this edge, is concaved,

gradually contracting to the convex beading 7 serving as a point of juncture between the base and the body 8 which is formed of six flattened panels 9—9 gradually widening toward their upper portions and finishing in straight horizontal edges. Above the body 30 is the concave neck 10 which gradually contracts the diameter of the pitcher at this portion and then expands, being finished by the pitcher-shaped edge 11 surrounded by the beaded-border 12. A handle portion is generally applied to this pitcher of which one design is indicated in dotted lines in the drawings.

What I claim is—

The design for the body of a pitcher as herein shown and described.

In witness whereof I have hereunto set my hand.

CHARLES C. WIENTGE.
